CENTER SUPPORT FOR VENETIAN
BLIND TILT RAILS

Brooks Walker, Piedmont, Calif.

Application January 10, 1949, Serial No. 70,112

5 Claims. (Cl. 160—177)

1

This invention pertains to improvements in a center support for Venetian blind tilt rails. Where we have used the term "center support," it is one generally applied to any support for the tilt rail in a Venetian blind intermediate the end supports of the tilt rail. Many types of metal bracket supports have been used to support tilt rails but many of them require a very heavy cutting of the tilt rail in order that the center support will not interfere with the required rotation of the tilt rail which is necessary in order to get tight closing of the slats in both directions of rotation of the tilt rail.

This invention pertains to an improved method of constructing and attaching the center supports in which material such as tape is attached to the head member by passing through a slot in the head member and having a rigid or flexible element pass through a loop in the flexible tape which prevents the loop from passing downward through the slot to anchor suitably the tape to the head member. The tilt rail is recessed to a point in line with the pivots in the end supports for the tilt rail. The tilt rail is slotted so that the tape can go through the tilt rail to be secured by another loop and filler for the loop that is wider than the slot. This provides a flexible support for the tilt rail which can be mounted in line with one of the intermediate ladder tapes which supports the slats in a conventional Venetian blind. This construction is particularly adapted to offset lift cords which permit the slats to be removable as is disclosed in my issued U. S. Patent No. 2,200,349.

To facilitate the removal of the tilt rail, tapes, slats, and bottom rail from the head member and tilt mechanism, it is sometimes necessary to make the center support detachable without having access to the top of the head member which may be secured to the window frame. This is accomplished in this invention by making the tape detachable by a detachable pin connection. By removing the detachable pin from the loops in the center support tape, the center support can be detached from the head member or tilt rail for separation of the tilt rail from the head member.

Other forms of the invention include methods by which the tilt rail is supported by flexible strap, either metal or tape or cord, passing around the tilt rail and anchored to the head member. It is realized that flexible tapes for supporting tilt rails have been used previously; however, it has been found that it is sometimes necessary to attach an additional block or spacer

2

to the tilt rail underneath the flexible support so as to change the contour of the tilt rail in order that the support for the tilt rail will keep the center of the tilt rail in approximately the same position as is accomplished by the end pivots throughout the tilting operation, which is not necessarily accomplished if the ordinary contour of the tilt rail is used and the tape-around type of center support is used.

10 Another form of the invention involves a method whereby the center support is a flexible element, is anchored at points spaced apart from the vertical center line of the head rail, and is extended through the head member to provide 15 a support for the tilt rail which will keep the tilt rail supported in approximately the same position relative to the head member as is accomplished by the tilt rail end pivot supports.

Another object of the invention is a means 20 whereby the tilt rail is supported from a point near the upper surface of the head member rather than below said head member.

Another object of the invention is an improved 25 and simpler method of supporting a Venetian blind tilt rail.

Another object of the invention is to provide an improved method of attaching a tape to a Venetian blind rail or head member.

Other objects of the invention will be more 30 clearly pointed out in the attached specifications and claims.

I have illustrated my invention by way of example in the accompanying views in which:

Figure 1 is a side elevation, partly cut away, illustrating one form of the invention.

Figure 2 is an enlarged view of a portion of the blind illustrated in Figure 1 taken at the center support.

Figure 3 is similar to Figure 2 but shows the 40 tilt rail in the tilted position.

Figure 4 is a perspective view of an enlarged section of a portion of the head member and a portion of the tilt member, showing another form of center support with a detachable unit 45 at the center.

Figure 5 is a sectional view of a portion of a Venetian blind including head member, tilt member, and first slat, showing another form of the invention.

Figure 6 is an end view of a portion of a Venetian blind, partly in section and cut away, showing another form of the invention.

In all views, similar numerals indicate corresponding parts in the various views.

55 In Figures 1, 2, and 3, I have shown a Vene-

tian blind in which a head member 10 supports brackets 12 and 12a which support the tilt rail 11. Bracket 12 is a tilt mechanism operated by tilt cords 13 of any conventional design and is suitably attached through a flexible rotation transmitting plate 11c to the tilt rail 11, to provide the necessary rotational control to the tilt rail 11. At the other end, pivot pin 11b forms the pivotal support to bracket 12a.

Tilt rail 11 supports the ladder tapes 6 which in turn support the slats 5 in spaced relationship, and the bottom ends of the ladder tapes are attached to bottom rail 9, all in the conventional manner. Other types of ladder tapes may be employed of metal, hinge type, wire type, etc., if desired. Lift cords 15 are preferably used in the offset position as shown with one toward the room face of one ladder tape and the other toward the window face of the ladder tape at the other end of the blind, in a manner similar to that illustrated in my issued U. S. Patent No. 2,200,349.

The center support tape 20 consists of a looped piece of webbing, preferably of a size and appearance similar to the side members of the ladder tapes 6. The upper end of this webbing is looped and passes through a saw slot or pierced slot in the head member 10. At the upper end of the loop, a piece of Venetian blind cord, pin, rod, wire clip, or other suitable member passes through the loop and thus prevents the loop from being pulled down through the saw slot in head member 10. This provides a suitable support for the upper end of the flexible tape which forms the center support. The lower end of the loop passes through a cut-away section 11a in tilt rail 11, preferably being cut away to a depth equal to the distance of pins 11a and 11b below the upper surface of tilt rail 11. A saw slot pierces the tilt rail to provide an opening at the bottom of the tilt rail at least equal to the width of the center support tape 20.

At the loop at the bottom of the tape 20, another piece of lift cord 22, or other suitable fastener, is inserted through the loop in said tape 20. Any suitable material may be placed through the loop to form a detachable connection between the webbing and the tilt rail to support it suitably at the point of the center support 20. A recess may be provided at the bottom of the tilt rail to receive the cord or filler 22, so that it is not below the lower surface of tilt rail 11, if the projection of this attachment below the lower surface of the tilt rail forms any visual operation objection.

Where it is necessary to provide a further detachable feature, or a detachable feature of another type, loops in the supporting tape, as illustrated in Figure 4, may be connected by a pin such as 21 which connects the loops 20a in the flexible supporting tape 20 which forms the center support. With a detachable pin 21 support through the loops of the tape 20, tape 20 may form a loop passing around fillers 21 and 22, as shown, or it may form a single thickness support as where the webbing goes through the saw slot and is tacked to the head member and to the tilt rail, respectively, or each end of the single thickness tape could have a loop formed to receive the retainers 21 and 22. By these constructions, the center support can be readily detached for dismantling the tilt rail, slats, and bottom rail from the head member, as when it is necessary to do so in mounting the blind, or for window washing, or for other purposes.

In Figure 5, I show another form of the invention in which the head member 10 supports the tilt rail 11 at its center or intermediate points by means of a flexible element 50 which may be metal, tape, piece of webbing, or a piece of cord suitably secured to the head member as by a loop through a slot. The upper end of loop 50a is prevented from returning through the slot by inserting a cord or filler 21. Flexible element 50 then passes around the tilt rail 11 to provide a suitable support.

Where the contour of the tilt rail 11 is such that the flexible support 50 will not maintain the center X of the tilt rail in the same position relative to the head member as is provided through the end pivoting supports for the tilt rail, it may be necessary to provide an added attachment 12a which may be suitably secured to the tilt rail by pins 11a or other suitable means to increase the cross-sectional area of tilt rail and attachment, so that in the tilted position the bottom of the tilt rail is maintained in the desired position relative to the head member 10. In the tilted position, since the slats come up against the lower face of tilt rail 11 as shown in Figure 5, the attachment 12a does not interfere with the closing of the slats next to the tilt rail, but does improve the action of the center support in passing around the tilt rail while not requiring the increased cross section of the tilt rail throughout its length with increased cost of added unnecessary material. Attachment 12 is preferably only about as long as the width of the flexible element 50.

In Figure 6, I have shown another form of the invention in which a head member 10 supports tilt rail 11 by means of flexible elements 40 which are secured to the head member and pass around the tilt rail but are spaced apart where they go through the head member at a suitable distance, so as to maintain point X of the tilt rail in the same relative position, as is accomplished by the pivots at the end of the tilt rail, whether the tilt rail is in the horizontal position, as shown, or in the tilted position as shown by dotted line. Flexible element 40 may be a cord with knots above the head member as shown, or it may be a flexible tape passing through slats and the head member and tacked to the head member adjacent the upper edges of the saw slots 10a and 10b, or a detachable pin may be used in one side through loops in a tape similar to the construction shown in Figure 4, but with the loop being attached to the head rail as shown in Figure 6 through two slots that are spaced apart, rather than through one central slot.

The lift cord 15 is shown passing down past the outside of the tilt rail and past the tape going through an opening in the ladder tape near the first slat.

Lift cords 15 could, of course, go down through route holes in the tilt rail at the center thereof with a center support constructed as shown in Figure 6. The lift cords would then go through route holes in the slats in a conventional manner. The lift cord could go through a notch in the tilt rail 11 with a center support constructed as shown in Figure 5; the lift cord would then go inside the side member of the ladder tape.

I do not wish in any way to limit myself to the exact details or mode of operation set forth in the specification and drawings, for it will be obvious that wide departure may be made in the way of details without departing from the

spirit and scope of my invention which is set forth in the following claims.

I claim as my invention:

1. In a Venetian blind a head member, a tilt rail disposed beneath said head member and pivotally connected thereto adjacent its ends on horizontal axes, a vertical slot extending through said head rail intermediate said pivotal connections and its side edges and disposed in parallelism with said axes, a flexible tape member supportedly engaged with said tilt rail intermediate its ends, and said tape member including a two-ply portion of a combined width equal to substantially the width of said slot, said two-ply portion extending through said slot and terminating in a loop above the upper edge of the slot, and an elongated member removably disposed within said loop, said member distending said loop to a width greater than that of the slot for retaining the tape in tilt rail supported position.

2. The structure according to claim 1, wherein in said tilt rail is provided with a slot in vertical alignment with said slot in the head member in the normal horizontal position of the tilt rail, said tape member further including a two-ply portion extending through said last slot and terminating in a loop, and a member removably disposed in said loop and distending same to a width greater than that of said last slot.

3. The structure according to claim 2 together

15 with a depression in the normally upper face of said tilt rail communicating with said last slot, said depression being defined by a convex wall on each side of the slot for rolling engagement with 5 said tape member upon rotation of the tilt rail.

10 4. The structure according to claim 2, wherein in said two-ply portions are removably connected intermediate the head member and the tilt rail.

15 5. The structure according to claim 1, wherein in said tape member further includes a relatively large loop portion beneath the head member and which transversely encircles said tilt rail and provides said supporting engagement.

BROOKS WALKER.
